UNITED STATES PATENT OFFICE

ARTHUR G. STEVENSON, OF ROCHESTER, NEW YORK

LIGHTER

Application filed May 31, 1928. Serial No. 281,969.

This invention relates to a lighter for cigars, cigarettes, pipes, or other uses, and has for its principal object the provision of a more satisfactory and efficient lighter than those heretofore known.

Another object of the invention is the provision of a lighter which may be manufactured easily and cheaply.

A further object is the provision of a lighter which is small and compact, and one which may be mounted easily and quickly in any desired position, such as upon an automobile.

It is still another object of the invention to provide a lighter which will operate satisfactorily and with a minimum of care or attention on the part of the user.

To these and other ends the invention resides in certain improvements and combinations of parts, all as will be hereinafter more fully described, the novel features being pointed out in the claims at the end of the specification.

In the drawings:

Fig. 1 is an elevation of a device embodying a preferred form of the invention, illustrating it as applied to a member which is shown partly in section;

Fig. 2 is a front elevation of the device;

Fig. 3 is an enlarged plan of one end of the holder with the torch removed;

Fig. 4 is an elevation of the torch removed from the holder;

Fig. 5 is a longitudinal section taken centrally through the torch;

Fig. 6 is a longitudinal section through a portion of the holder showing the torch in position for lighting the wick;

Fig. 7 is an enlarged view somewhat similar to Fig. 1 but showing the holder in section;

Fig. 8 is an enlarged view somewhat similar to Fig. 2, also showing the holder in section, the plane of the section being at right angles to the plane of Fig. 7;

Fig. 9 is a transverse section taken substantially on the line 9—9 of Fig. 7, and

Fig. 10 is an end view of the wick end of the torch.

Similar reference numerals throughout the several views indicate the same parts.

The lighter consists, in general, of a holder, and a torch element which may be inserted into and withdrawn from the holder, the parts being so arranged that the torch will be lit automatically as it is withdrawn. When the torch is removed from the holder, it will remain lit if desired for a considerable period of time, and as there is no physical connection between the torch and the holder, the former may be passed around from one to another in a crowd and may be removed as far as desired from its holder.

The holder consists in part of a tubular body 15 preferably formed of a suitable insulating material. A plug 16 closes one end of the body, as shown especially in Figs. 7 and 8, this plug having a cup-shaped recess 17 formed therein.

The holder 15 is provided with means for attaching it conveniently to any desired article, such as the dashboard of an automobile. This means may comprise a U-shaped bracket member 18 (Figs. 1 and 7) which has a screw 19 threaded therein as shown. By tightening the screw 19, the member 18 may be clamped to any suitable projection, ledge, or shelf, such as that indicated by the numeral 20 in Fig. 1.

For connecting the body 15 of the holder to the bracket 18, there are preferably metallic members attached to the bracket and partially encircling the body of the holder. One of these members, designated as 21 and shown in section in Figs. 6, 7 and 8, and in plan in Fig. 3, is fixed by suitable means to the bracket 18 and has an annular portion encircling one end of the body 15 of the holder, this annular portion having a down-turned flange 22 at its edge as shown.

A somewhat similar member 23 is fixed to the other end of the U-shaped bracket 18 and encircles the body 15 of the holder adjacent a slight shoulder 24 formed thereon. A flange 25 on the member 23 is turned over so as to lie against the body of the holder, as illustrated in Figs. 1, 7 and 8. The body 15 of the holder is thus securely affixed to the bracket 18 by means of these members 21 and 23.

A passageway extends longitudinally through one side of the holder 15, and in this passageway is mounted a rod 30 formed of suitable electrical conducting material, the rod being shown in Figs. 6 and 8. As is also illustrated in these figures, a cross passageway extends transversely through the wall of the holder 15 and intersects the rod 30, a short conducting rod 31 being placed in this passageway. The inner end of the rod is substantially flush with the inner surface of the tubular holder 15, but the rod is shorter than the thickness of the wall of the holder, and an insulating plug 32 covers the outer end of the rod 31 and prevents external contact therewith.

Preferably the rod 31 is of somewhat smaller diameter than the rod 30, and the former is forced into a hole bored through the latter so that a good electrical contact is produced between the two rods. The lower end of the rod 30 may be threaded as at 33, and a member 34, adapted to have a wire or other suitable electrical conductor 35 secured to it by solder or by other means, is arranged to be screwed onto the threads 33 in order to connect the rods 30 and 31 to a source of current.

The retaining member 21 has a lug or lip 40 formed thereon, which lies against one side of the holder 15, as illustrated in Figs. 1, 6 and 8. Beneath this lip a passageway is formed transversely through the wall of the holder 15, and in this passageway is placed a sleeve or bushing member 41 having the inside diameter of its inner end slightly reduced so as to retain a ball 42 pressed inwardly by a coiled spring 43.

The retaining member 23, near the opposite end of the holder from the member 21, is provided with a lip or lug 45 somewhat similar to the lip 40 on the member 21. A short screw 46, shown in Fig. 8, is threaded through this lip 45. The screw 46 is not of sufficient length to reach the rod 30, but always remains insulated therefrom, no matter how far it is screwed up. The purpose of this screw is to provide a convenient means of attaching an electrical conductor, as will be described below.

The torch element which cooperates with the holder is best illustrated in Figs. 4 and 5. It comprises a tubular body portion 50 having an outside diameter slightly less than the inside diameter of the holder 15, so that it may be easily inserted in or withdrawn from the holder. One end of the tubular body is closed by a screw cap 51, which may be removed for the purpose of replenishing the fuel within the torch, or for changing the absorbent packing 52 which holds the fuel. A wick 53 passes through the packing 52 and extends out of one end of the torch through a wick-holding bushing 54. This wick-holding element is preferably a cylindrical extension formed on a cup-shaped sleeve 55 which fits within the

tubular torch and extends some distance from the end of the torch toward the middle, as shown in Fig. 5. The parts 54 and 55 are made of electrical conducting material, while the body 50 of the torch is preferably of insulating material.

A ring 56, of metal or other conducting material, encircles the body of the torch at a point somewhat spaced from the wick end thereof. A short rod or plug 57 extends through the wall of the torch and provides an electrical connection between the ring 56 and the cup-shaped sleeve 55.

Mounted on the wick end of the torch, and extending around the wick-holder 54, is a member 58 having a dished or cupped portion 59 which extends forwardly from the end of the torch. It will be understood that the member 58 is annular, its center being cut away, and the wick-holder 54 is substantially in alignment with the cut-away portion. Thus the inner edge of the dished portion 59 is spaced from the wick holder 54 to form a spark gap between the wick holder and the member 58. In the embodiment illustrated, the dished or cupped portion 59 of the member 58 is substantially in the shape of a frustum of a cone, but other suitable shapes could be used if desired, or a single prong may be used to form the spark gap instead of having an annular member completely encircling the wick holder.

A ring-like cylindrical flange 60, formed on the member 58, encircles the body 50 of the torch, and is retained thereon by any suitable means such as the crimps 61, shown in Fig. 5.

The ring 56 is spaced from the ring-like portion 60 of the member 58 a distance substantially equal to distance by which the ball member 42 is offset from the rod 31. Thus, when the torch is moved relative to the holder to such a position that the ring 60 is opposite the rod 31, the ball 42 will then be in contact with the ring 56, this position of the parts being illustrated clearly in Fig. 6.

A groove 65 is formed in the body 50 of the torch in such position that it will be opposite the ball 42 when the torch is seated against the plug 16, as illustrated in Fig. 8. When the torch is in this position, the ball 42 acts as a spring detent to hold the torch seated against the end of the holder and to prevent it from becoming jarred loose. The annular shoulders on the plug 16 provide a support for the end of the torch, while the wick and the spark gap parts are received within the cavity 17. They are thus prevented from becoming bent by contact with the end of the holder.

When the lighted torch is replaced in the holder and thrust to its normal position against the plug 16, the end of the torch coming into contact with the annular shoulder on the plug renders the cavity 17 practically a

sealed chamber, and thus the flame is immediately extinguished due to lack of oxygen. As the torch is withdrawn from the holder, sufficient air is admitted through the openings 5 66 and 67 to support combustion.

In use, the holder is fixed to any convenient support and is wired up to a source of high tension electrical current. For purposes of illustration, the device is shown in Fig. 1 as 10 being applied to a metal ledge 20 which may be, for example, part of the dashboard or other metal portion of an automobile. This portion 20 is grounded, as is illustrated diagrammatically by the conductor 70 and the 15 conventional representation of the ground 71. A battery is indicated conventionally at 72, one terminal of the battery being grounded and the other terminal being connected by a conductor 73 to a spark coil or other high tension producing device 74. The conductor 20 35, which has been mentioned above, is connected to the high tension side of the spark coil 74.

It is obvious that any suitable source of 25 electrical current could be used, and that the above parts are cited merely by way of example. The spark coil might be omitted if a suitable source of current were available without the use of the coil.

With the parts wired up in the manner indicated in Fig. 1, it is obvious that the rod 31 30 will be electrically connected to the source of current through the rod 30, the screw member 34 and the conductor 35. Likewise, the ball 43 will be electrically connected to the 35 other side of the source of current through the lip 40, retaining member 21, bracket 18, metallic member 20, and conductor 70.

Now as the torch is withdrawn from the 40 holder, the ring 56 will be in contact with the ball 42 at the same time that the ring 60 is opposite the rod 31, as illustrated in Fig. 6 and as described above. Since the ring 56 is electrically connected to the wick holder 45 54, and since the dished portion 59 of the member 58 is electrically connected to the ring portion 60, it follows that the two members 54 and 59 will be connected to opposite sides of the source of current, and obviously 50 they will form a spark gap across which a spark will jump. This spark will ignite the torch, which may then be used as a lighter for cigars, cigarettes or pipes, or for any other purpose, and may be removed as far as desired from its holder. Since the torch 55 is provided with its own supply of fuel, it will continue to burn for any reasonable length of time desired.

When the use of the torch has been completed for the time being, it may be reinserted in its holder, and the flame will be snuffed out automatically, as was pointed out above. The ball 42 functions to retain the torch 60 frictionally within the holder, although it does

not prevent its removal therefrom by a slight pull.

The dished or cup-like shape of the spark element 59 is particularly advantageous since it forms a pocket surrounding the wick-holder 70 54, which pocket retains a certain amount of fuel vapor, holding it in close proximity to the wick and aiding the torch to light easily.

Whenever it is impossible or inconvenient 75 to clamp the torch holder on a metallic member which is connected to one side of the source of electric current, it may be clamped to any convenient ledge or support and an electrical wire may be attached to the frame 80 of the holder by means of the screw 46. This wire would lead, of course, to the opposite side of the source of current to that which was connected to the conductor 35. Any electrical connection to the screw 46 accomplishes 85 the same purpose as though the connection were made to the bracket 18, since the screw 46 is threaded into the lip 45 which is part of the retaining member 21, which latter is secured to one end of the U-shaped bracket 18. 90

The open end of the holder 15 may be provided with rounded shoulders 80 so that the torch may slide easily into the holder without the necessity of aligning it accurately therewith prior to the introduction of the torch. 95 The shoulder of the member 58 may be somewhat rounded for the same purpose.

It is not essential that the rod 31 come into 100 actual contact with the ring 60 during the withdrawal of the torch, since if the end of the rod is slightly spaced from the ring the high tension current will jump easily from the rod to the ring and the desired spark between the members 54 and 59 will result, thus igniting the torch.

While one embodiment of the invention has 105 been disclosed, it is to be understood that the inventive idea may be carried out in a number of ways. This application is, therefore, not to be limited to the precise details shown, but is intended to cover all variations and 110 modifications thereof falling within the spirit of the invention or the scope of the appended claims.

I claim as my invention:

1. The combination with a torch having a spark gap thereon, of a holder in which said torch is normally received, said torch and holder being capable of movement relative to each other, and means for causing a spark across said spark gap while said torch is being withdrawn from its normal position in the holder.

2. The combination with a torch having a spark gap thereon, of a holder in which said torch is normally received, said torch and holder being capable of movement relative to each other, electrical conductors on said torch operatively connected to said spark gap, and electrical conductors on said holder arranged 125 130 135

- to be in contact with the conductors on the torch as said torch is being withdrawn from its normal position in the holder.
3. The combination with a torch having a spark gap thereon, of a holder in which said torch is normally received, said torch and holder being capable of movement relative to each other, electrical conductors on said torch operatively connected to said spark gap, and electrical conductors including a spring 5 pressed detent on said holder arranged to be in contact with the conductors on the torch as said torch is being withdrawn from its normal position in the holder.
4. The combination with a torch having a spark gap thereon and including a pair of spaced electrical conductors extending circumferentially around said torch and electrically connected to said spark gap, of a holder 10 for said torch, said torch and holder being capable of movement relative to each other, and a pair of electrical conductors on said holder spaced from each other in the direction of relative movement substantially the 15 same distance as the spacing between the conductors on the torch in the same direction, said conductors on the holder being arranged to be in contact with the conductors on the torch when said torch and said holder are moved to a predetermined position relative 20 to each other.
5. A torch including a tubular body portion of insulating material, a wick-holding element formed of an electrical conducting material, an electrical conducting ring 25 extending circumferentially around said torch and connected to said wick-holding element, and a conducting member spaced from said wick-holding element to form a spark gap 30 between said member and said element.
6. A torch including a tubular body portion, a wick-holding element formed of an electrical conducting material, and an electrical conducting member extending around 35 said wick-holding element and spaced therefrom to form a spark gap between said member and said element, said member being dished to form a pocket for holding fuel vapor in proximity to said spark gap.
7. A lighter including a tubular holder 40 having a pair of electrical conducting elements on the inner wall of said holder, said elements being spaced from each other in a direction longitudinally of said holder, and a torch adapted to be inserted into and withdrawn from said tubular holder, said torch including a wick, a metallic wick-holding element having an electrically connected portion 45 extending circumferentially around said torch and arranged to cooperate with one of the conducting elements on the holder when the torch is in a predetermined position relative to the holder, said torch also including a metallic member spaced from said wick-holding element to form a spark gap between said 50
- member and said element and an electrically connected portion in the form of a ring extending circumferentially around said torch, said ring being arranged to cooperate with the other of the conducting elements on the holder when said wick-holding element cooperates with one of the conducting elements on the holder. 70
8. The combination with a torch including a spark gap and a pair of electrical conductors operatively connected to said spark gap, of a holder for said torch, said torch and holder being capable of relative movement, said holder including a pair of electrical conductors for cooperation with the conductors 75 on the torch when the torch is moved to a predetermined position relative to the holder, one of said conductors being in the form of a detent for holding the torch and the holder yieldably in predetermined position relative 80 to each holder.
9. A holder for an electrically operated lighter torch, said holder including a U-shaped bracket member, a tubular body portion formed of insulating material and attached to said bracket member, and a pair of electrical conductors on the inner wall of said body portion arranged to cooperate with a torch inserted in said body portion, one of said conductors being electrically connected 85 to said U-shaped bracket.
10. A holder for an electrically operated lighter torch, said holder including a U-shaped bracket member, a tubular body portion formed of insulating material and attached to said bracket member, and a pair of electrical conductors on the inner wall of said body portion arranged to cooperate with a torch inserted in said body portion, one of said conductors including a movable element 90 and means tending to move said element toward the center of said tubular portion. 100
